(57) **CLAIM**

The ornamental design for a passage-gate, as shown and described.

DESCRIPTION

FIG. 1 is a front view of a passage-gate (i.e. for train or subway stations) showing my new design;

FIG. 2 is a 3D front view thereof;

FIG. 3 is a top view thereof;

FIG. 4 is a side view thereof; and,

FIG. 5 is a rear view thereof.

The portions of the drawings illustrated in broken lines are directed to the environment of the design and form no part of the claimed design.
